UNITED STATES PATENT OFFICE.

FREDERICK W. ROBERTSHAW, OF PITTSBURGH, AND GEORGE A. ROBERTSHAW, OF GREENSBURG, PENNSYLVANIA.

BURNER SYSTEM.

Application filed June 3, 1920. Serial No. 386,162.

To all whom it may concern:

Be it known that we, FREDERICK W. ROBERTSHAW and GEORGE A. ROBERTSHAW, both citizens of the United States, residing, respectively, at Pittsburgh, Allegheny County, Pennsylvania, and Greensburg, Westmoreland County, Pennsylvania, have invented a new and useful Improvement in Burner Systems, of which the following is a full, clear, and exact description.

The present invention relates particularly to burner systems, and more particularly to systems of this type employing a pressure burner.

15 The principal object of the present invention is to provide a system in which the pressure burner may be located at any desired position and controlled either manually or by a suitable thermostat.

20 Another object of the invention is to provide a thermostatic system comprising a pressure burner adapted to receive a combustible mixture of air and gas, oil and gas, or the like, which burner may occupy any 25 convenient position and which is controlled indirectly by a thermostat through the medium of one of the fluids or gases supplied thereto.

Still another object of the present invention is to provide a pressure burner of the 30 class described, supplied with a combustible mixture through a plurality of valves, which valves may both be operated by a diaphragm, the position of which is dependent upon the 35 amount of pressure directed thereagainst by the action of the controlling thermostat.

A further object of the invention is to provide a system of the nature described 40 controllable at will by either the action of a thermostat or manually without necessitating any change in the system.

45 A still further object of the invention is to provide a safety system of this character with means whereby the cessation of flow of one of the combustibles will automatically shut off the burner.

An additional object of the present invention is to provide a system in which the proportion of combustibles supplied may be 50 varied at will and the burner brought into operation or taken out of operation without affecting this proportion.

The foregoing and other objects, together with their attendant advantages, will be apparent as the invention becomes better un-

derstood by reference to the accompanying specification and drawings forming a part thereof, it being premised that changes may be made in the various details and the manner of operation within the scope of the 60 appended claims without departing from the spirit of the invention.

Figure 1 is a diagrammatic view partly broken away showing one form of system embodying the present invention.

65 Figure 2 is an enlarged detail view partly in section illustrating the operation of certain of the valves.

Figure 3 is a diagrammatic view partly in elevation and partly broken away of a 70 slightly modified form of system.

Figures 4 and 5 are diagrammatic views of further modifications, and

Figure 6 is a detail view of a modification.

At the present time it is customary to 75 provide pressure burners receiving a combustible supply of steam, oil and air, or gasoline and air, or other suitable mixtures. In such burners, if the supply of air under pressure is suddenly cut off, the gas flame 80 will flare out thereby endangering the lives of those employed in the vicinity of the burner. By means of the present invention this danger is entirely eliminated.

It is also desirable in systems employing 85 pressure burners to provide means for operating the burner on a combustible mixture of predetermined proportions of the different fluids or gases. In some instances a pilot flame burns continuously after a pre-determined temperature has been reached, the main supply of the combustible being cut off by thermostatically controlled valves. By means of the present invention, the main 90 supply of the combustion ingredients may be cut off or admitted to the burner without effecting the proportions of the individual combustion ingredients. With the system 95 illustrated in the drawings this cutting off, or admitting, may be accomplished 100 either thermostatically or manually.

Referring more particularly to the drawings, there is illustrated a system comprising an air supply 2 and a gas supply 3. Inserted in each of these combustion ingredient supply lines is a suitable index cock 4, which controls the amount of the individual combustion ingredient passing therethrough, thereby permitting an accurate proportioning of the different combustion ingredients.

In the air supply 2 there is provided a valve 5 comprising a suitable seat 6 and a cut-off 7. The cut-off is normally held in engagement with the seat 6 to prevent the passage 5 of air through the valve by means of a spring 8. A similar valve is provided in the gas supply, the corresponding parts being indicated by the same reference characters with the letter *a* affixed thereto. Both the 10 valve 5 and the valve 5^a are preferably provided with integral by-passes 9 controlled by a suitable screw 10. In Figure 2 these by-passes are illustrated diagrammatically for the sake of clearness. From the valves 15 5 and 5^a the air and gas may pass to a burner manifold 11 from which is supplied a series of burners 12. In Figure 1 these burners are shown extending below a tank 14 adapted to contain a solder bath of any 20 desired composition. It will be understood that the burners 12 are preferably of the pressure type being supplied by a source of air and gas under pressure.

Connected to the air supply 2, there is indicated a branch 15 leading to one side of a valve 16 which may be of any desired construction adapted to be operated by the thermostatic element 17 immersed in the solder bath in the tank 14. The opposite, 25 or outlet side of the valve 16 is connected by a branch 18 to the casing 19 containing a diaphragm 20 suitably mounted therein.

Assuming the temperature of the bath in the tank 14 to have fallen below a predetermined point, the valve 16 will be opened by the action of the thermostatic element 17 to allow air to pass through the branch pipes 15 and 18 to the diaphragm casing 19. This air under pressure will depress the 40 diaphragm 20, thereby opening both the cut-off members 7 and 7^a through the rods 21. This will supply an additional amount of combustion ingredients to the burner manifold 11, which feeds the burners 12, thereby 45 producing a hotter flame which will result in raising the temperature of the solder bath. As soon as the desired temperature has been reached, the valve 16 will be closed thereby cutting off the supply of air to the 50 casing 19 and permitting the diaphragm 20 to return to its normal position. This will result in a closing of the valves 5 and 5^a, as will be well understood. The portion 55 of the casing 19 below the diaphragm may be provided with a bleed opening 22, permitting the unrestricted operation of the diaphragm, and the branch line 18 may in like manner be provided with a bleed opening 24. This latter opening is preferably 60 controlled by a screw 25. It will be obvious that at no time is the opening 24 opened to such an extent as to prevent the building up of a diaphragm operating pressure within the casing 19.

One of the valuable features of the pres-

ent invention comprises the insertion in the branch line 15 of a valve 26, preferably manually controlled. By means of this valve, the air pressure to the casing 19 may be cut off at will causing the valves 5 and 5^a to close without affecting the proportion of the different combustion ingredients as controlled by the index cock 4.

It will be obvious that if desired, gas may be supplied through the pipe 2 and air 75 through the pipe 3 without affecting the operativeness of the present system. In case this reversal of the combustion ingredients is made, it is desirable that a space 27 be left between the adjacent ends of the independent 80 rods 21 so that the air valve will not be opened until slightly after the opening of the gas valve. This feature is important in some installations as it prevents the accidental blowing out of the flame.

In Figures 1 and 2 of the drawings we have illustrated the valves 5 and 5^a connected by a yoke 28. This yoke holds the valves in predetermined positions so that a free operation thereof is permitted. At the same time, 90 due to this construction, access may be easily had to the interior of either of the valves for the purpose of inspecting, repairing or cleaning the same.

It will be apparent from the foregoing 95 description that the solder bath forms no part of the present invention, but is shown merely as one use to which the system may be placed.

Another important feature of the present 100 invention resides in the provision in the casing 19 of an adjustable screw 29 by means of which the diaphragm 20 may be manually depressed to hold the valves 5 and 5^a in open position, irrespective of the operation 105 of the thermostat. Due to this construction, our system readily adapts itself to use either with or without thermostats, thereby greatly increasing its value.

In Figure 3 there is illustrated a slightly 110 modified form of our invention comprising a gas supply 30 and an air supply 31. In this system, the gas supply 30 passes through a valve 32 which may have the same construction as that heretofore described, controlled by a diaphragm 34 in the casing 35. Operating pressure in the casing 35 is obtained through the branch 36 having a manually operable valve 37 therein corresponding to the valve 26 described heretofore. This branch is also provided with a thermostatically operated valve 38 which may be similar in construction and operation to the valve 16. As gas is the operating medium in the present instance, the bleed 115 opening above the diaphragm preferably communicates with a pipe 39 which may lead to a suitable burner for preventing the escape of the released gas into the atmosphere.

The air supply in this system may be controlled by a valve 40. After passing the valves 32 and 40, respectively, the gas and air may be conducted to a common burner connection 41 functioning as a manifold, or supplying an individual pressure burner.

In Figure 4 there is illustrated a system employing our invention and comprising only one combustion ingredient supply line. 10 This system corresponds generally to the construction shown in Figure 3, and the corresponding parts are indicated by the same reference characters with the letter "a" affixed thereto. With this arrangement, the combustion ingredient passing through the line 30^a is controlled by a main valve 32^a which is, in turn, operated by a diaphragm within the casing 35^a. The branch for the actuating fluid for the diaphragm is controlled either by the manually operable valve 37^a or the thermostatically controlled valve 38^a, as will be apparent.

In Figure 5 there is illustrated a form of our invention in which no thermostatic valve is employed. This arrangement illustrates the safety feature of our invention by providing means for preventing flaring out of the gas in case the air supply is suddenly cut off. This arrangement comprises 50 generally the arrangement disclosed in Figure 3, and the same reference characters with the letter "b" affixed thereto have been used to designate the corresponding parts.

It will be apparent that with the branch 36^b connected to the air supply line 31^b failure of the air supply will result in relieving pressure from the upper surface of the diaphragm in the casing 35^b, thereby 40 closing the valve 32^b. This feature is highly desirable as it prevents accidents due to flaring out of the gas flame.

In actual practice it has been found desirable to make the valve operating stem 21, 45 as shown in Figure 2, separate from the diaphragm 20. By reason of this construction binding action is not transmitted by the diaphragm to the valve operating stem.

It has also been found highly desirable 50 in actual installations to provide with systems such as shown in Figures 1 and 2, a device for adjusting the relative positions and times of operation of the cut-offs 7 and 7^a. Such a device is illustrated in these figures and is shown in detail in Figure 6 in which figure parts corresponding to parts described in connection with Figures 1 and 2 are designated with the same reference characters with the letter "c" affixed thereto. In this drawing, one of the rods 21^c, within the yoke 28^c is provided with an opening 50 extending therethrough for preventing rotation of the rods while applying or adjusting an internally threaded cap 51 thereon. This cap may also be provided

with an opening 52 permitting the insertion of a suitable tool for turning the same. The cap is illustrated as having a set screw 53 for holding it in adjusted position. It will be apparent that a device of this nature enables an accurate and adjustable control of the valves. 70

The advantages of the present invention reside in the safety system provided by means of which the flow of the air where it is used to operate the diaphragm will cut off the supply of gas and prevent dangerous flaring of the burner. 75

Further advantages arise from the means for permitting dual control of the valves 80 and for permitting cutting off the amount of supply of combustion ingredients at will without changing the proportion previously established.

We claim:

1. A thermostatically controlled system comprising a combustion ingredient supply line, a valve controlling the flow through said line, a diaphragm for operating said valve, a thermostat, means controlled by said thermostat for directing an actuating medium from said supply line against said diaphragm to operate the valve, and means for controlling said valve independently of said thermostat, substantially as described. 95

2. A thermostatically controlled system, comprising a combustion ingredient supply line, a valve controlling the flow through said line, a branch connected to said line, a thermostat controlling the flow through said branch, a valve operating diaphragm controlled by the pressure through said branch, and means operable independently of said thermostat for operating said diaphragm, substantially as described. 100

3. A thermostatically controlled system, comprising a plurality of combustion ingredient supply lines, a controlling valve in each of said lines, a diaphragm for operating said valves, a pressure branch connected 110 to one of said lines, a thermostat controlling the flow through said branch, means connecting the branch to the controlling diaphragm for operating the valves when the branch is opened by the action of the thermostat, and means operable independently of said thermostat for operating said valves, substantially as described. 115

4. A system of the class described, comprising a plurality of combustion ingredient supply lines communicating therewith, valves controlling the flow through said lines, a diaphragm casing, a diaphragm therein for operating the valves, a pressure branch connected to one of said lines and to 120 said diaphragm casing, a valve in said branch, a thermostat controlling the position of said last mentioned valve for controlling the passage of operating pressure to said diaphragm, and means independent 125 of said diaphragm, and means independent 130

- of said thermostat for operating said valves, substantially as described.
5. In a system of the class described, a plurality of combustion ingredient supply lines, normally closed valves in each of said lines, and a diaphragm for controlling all of said valves, one of said valves being operable by said diaphragm in advance of the other, substantially as described.
10. 6. In a system of the class described, a plurality of combustion ingredient supply lines, normally closed, valves controlling the supply through each of said lines, and a single means for operating said valves one in advance of the other, substantially as described.
15. 7. In a system of the class described, a combustion ingredient supply line, a valve in said line, a pressure controlled means for operating said valve, a branch from said supply line for supplying pressure to said means, and a manually operable valve in said branch, substantially as described.
20. 8. In a system of the class described, a combustion ingredient supply line, a valve in said line, a pressure controlled means for operating said valve, a branch from said supply line for supplying pressure to said means, a manually operable valve in said branch, and a thermostatically controlled valve in said branch, substantially as described.
25. 9. In a system of the class described, a plurality of valves, a yoke connecting the same, aligned operating rods secured to said valves, and an adjusting means intermediate the ends of said rods, substantially as described.
30. 10. In a system of the class described, a plurality of normally closed valves, operating rods therefor, said operating rods extending in alignment, means for operating said valves, and an adjustable member intermediate the ends of said rods and adapted to vary the distance between said rods for varying the time of opening of the valves, substantially as described.
35. 11. A valve mechanism, comprising a plurality of valves, a yoke maintaining an operative connection between said valves, and adjustable means carried by one of the valves for controlling the relative time of operation thereof, substantially as described.
40. 12. In a system of the class described, a combustion ingredient supply line, a valve in said line, a pressure controlled means for operating said valve, a branch from said supply line for supplying pressure to said means, and a plurality of independent means for controlling the flow through said branch, substantially as described.
45. 13. In a burner system, a plurality of combustion ingredient supply lines, valves controlling the flow through said lines, a diaphragm casing, a diaphragm therein for operating the valves, a pressure by-pass connected to one of said lines and the said diaphragm casing, a manually operable valve in said by-pass, a second valve in said by-pass, and a thermostat controlling the position of said second valve for controlling the passage of operating pressure to said diaphragm, substantially as described.
50. 14. In a burner system, a plurality of combustion ingredient supply lines, a valve in each of said lines, and valves having operating stems extending in alignment and freely spaced one from the other, and a diaphragm for controlling all of said valves, one of said valves being operable in advance of the other by an amount corresponding to said space, substantially as described.
55. 15. In a burner system, a plurality of combustion ingredient supply lines, valves controlling the supply through said lines, said valves having freely spaced operating stems extending in alignment, and a single means for operating said valves one in advance of the other by an amount corresponding to the space between said stems, substantially as described.
60. 16. In a burner system, a pressure supply line, a combustion ingredient supply line, a controlling valve in said combustion ingredient supply line, a diaphragm for operating said valve, a by-pass from said pressure line to said diaphragm for controlling the operation thereof, and a plurality of independently operable means for controlling the flow through said by-pass, substantially as described.
65. 17. In a burner system, a plurality of valves, a yoke connecting said valves, aligned operating rods secured to said valves and providing a space between the adjacent ends thereof, and an adjustable means for varying the amount of said space, substantially as described.
70. 18. In a burner system, a pressure supply line, a combustion ingredient supply line, a controlling valve in said combustion ingredient supply line, a diaphragm for operating said valve, a by-pass from said pressure line to said diaphragm for controlling the position thereof, thermostatic means for controlling the flow through said by-pass, and means operable independently of said thermostatic means for manually controlling the flow through said by-pass, substantially as described.
75. In testimony whereof, we have hereunto set our hands.
- FREDERICK W. ROBERTSHAW.
GEORGE A. ROBERTSHAW.
